UNITED STATES PATENT OFFICE.

PETER H. COLT, OF WARREN, PENNSYLVANIA.

FOLDING COOP AND CRIB.

1,223,257.

Specification of Letters Patent. Patented Apr. 17, 1917.

Application filed May 17, 1916. Serial No. 98,125.

To all whom it may concern:

Be it known that I, PETER H. COLT, a citizen of the United States, residing at Warren, in the county of Warren and State of Pennsylvania, have invented certain new and useful Improvements in Folding Coops and Cribs, of which the following is a specification, reference being had therein to the accompanying drawing.

10 This invention relates to certain new and useful improvements in a folding coop and crib for infants, the object being to provide a folding wheeled coop which can be readily converted into a crib.

15 The main object of my invention is to provide novel means for mounting the bottom frame so as to support the same in lowered or raised position in order to convert the device into a crib or coop as desired.

20 I am aware that I am not the first in the art to provide a folding coop and crib, but in prior devices it was necessary to raise the bottom upwardly from off of its lower supports and place the same in position upon 25 higher supports in order to convert the device when used as a coop into a crib, while in my improved construction, the bottom is mounted upon a double crank which can be swung into lowered or raised position so as 30 to convert the device into a coop or crib.

Other and further objects and advantages of the invention will be hereinafter set forth and the novel features thereof defined by the appended claims.

35 In the drawings,

Figure 1 is a perspective view of a portion of a folding coop and crib constructed in accordance with my invention.

Fig. 2 is a longitudinal vertical section.

40 Fig. 3 is a top plan view of the combined coop and crib in folded position.

Fig. 4 is a transverse vertical section showing the bottom frame in lowered position in order to convert the device into a coop.

45 Fig. 5 is a similar section showing the bottom frame in elevated position in order to convert the device into a crib, and

Fig. 6 is a detail transverse vertical section showing the bottom frame in vertical 50 position.

Like numerals of reference refer to like parts in the several figures of the drawing.

In carrying out my invention I employ a pair of side frames 1 and 2 preferably rectangular in shape covered with foraminated material as clearly shown, the side piece 1

being provided with lateral extensions 3 at each end, to each of which is connected by hinges 4, an end section 5, which is connected to an end section 6, by hinges 7, said end section 6 being connected to the side frame 2 by hinges 8, in order to allow the end sections 5 and 6 to fold inwardly to reduce the width of the device for the purpose herein-after fully described. The sections 5 and 6 are formed of rectangular frames covered with foraminated material of the same nature as of the foraminated material on the frames 1 and 2, and these frames 1, 2, 4, and 5 are preferably formed of wood highly finished to give an ornamental appearance, but of course, the same can be formed of any suitable metal without departing from the spirit of my invention.

The extensions 3 are provided with bearings 9 in which are mounted the trunnions 10 of a double crank 11 on which is pivotally mounted a bottom frame 12 having the usual wire fabric covering 13 for supporting a mattress 15, said frame being provided with eyes 16 for pivotally connecting the double crank 11 thereto in such a manner that the same is free to swing thereon. The frame 12 is of such a size that it fits snugly between the side and end frames of the device when in extended position as shown in Figs. 1, 2, 4 and 5, so as to hold the device in set-up position to form a crib or coop as the case may be. The double crank 11 when in lowered position normally assumes the position as shown in Fig. 4, that is, the crank portion does not hang in a vertical plane but obliquely, as shown in Fig. 4 so as to allow the bottom frame 12 to be swung upwardly rocking on the double crank as a pivot in order to assume the position shown in Fig. 3 when the device is in folded position. The bottom frame is supported by a cleat 17 carried by the frame 2, when in lowered position, and it will be seen that when the device is in the position shown in Figs. 1, 2, and 4, a coop is formed in which an infant can be placed and retained without any danger of the infant injuring itself in any way.

When it is desired to convert the device from a coop to a crib, the bottom frame is lifted upwardly by grasping the handle 18 and rocking the frame on the double crank as a pivot, and by drawing upwardly on the bottom frame the crank can be turned over, the same traveling on the arc of a circle as

shown by dotted lines in Fig. 5, and the bottom frame 12 will be raised into the elevated position as shown in Fig. 5.

- Secured to the bottom of the frame 12 at each end, is a tape 19 which is adapted to be placed over the top bar of the frame 2, and is provided with a button hole for engaging a button 20 secured to the frame 2, as shown in Fig. 5 for supporting the frame 12 when in raised position, said tape being folded on the frame under the mattress when the frame 12 is in lowered position as shown in Fig. 4. By this construction each end of the frame is supported by a canvas tape which can be folded under the mattress when the frame is in lowered position so that the supporting means for the frame when in lowered position is out of the way and cannot possibly injure the infant within the coop.
- 20 In order to provide additional means for holding the end sections in alinement when the coop is in use, I provide pivoted clips 22 which embrace the upper edges of the sections 5 and 6 as is clearly shown in Figs. 1, 25 4 and 5.

The end frames 6 carry blocks 22' having beveled faces adapted to be engaged by the bottom frame when the same is in lowered position so as to force the frames 5 and 6 30 outwardly into alinement so as to hold the device in set-up position.

The side frames 1 and 2 are provided with hangers 23 carrying stub axles 24 on which are mounted wheels 25 in order to allow the 35 device to be moved from place to place which practically forms a carriage which can be readily converted from a pen or coop into a crib.

- 40 When the device is in the position as shown in Figs. 1, 2 and 4, and it is desired to fold the device so that the same will occupy a small space, the handle 18 of the bottom frame 12 is grasped and lifted upwardly, the bottom swinging on the double crank 11 45 as a pivot until the same assumes the position shown in Figs. 3 and 6, the mattress and frame being substantially of the same width as the extensions 3 so as to allow the device to be folded as shown in Figs. 3 and 50 6, and when in this folded position, the crank will have a tendency to hold the bottom frame and mattress in vertical position as shown in Fig. 6.

From the foregoing description, it will be 55 seen that I have provided a combined fold-

ing coop and crib mounted on wheels having a fabric bottom carried by a double crank, the trunnions of which are mounted in end extensions of one side frame in such a manner that the bottom frame 10 be raised 30 and lowered in order to change the device from a coop to a crib and when in either position one side thereof will be supported by said double crank.

I claim:

1. A folding crib, comprising side pieces connected together by sectional end pieces, a double crank pivotally carried by one of said side pieces, a bottom frame pivotally mounted upon said crank, and means for 70 supporting said bottom frame in different horizontal planes.

2. A crib having a double crank pivotally mounted within the walls thereof, a bottom pivotally mounted upon said crank, and 75 means for supporting said bottom horizontally in different horizontal planes.

3. A folding crib, comprising side frames, one of said side frames being provided with lateral extensions, sectional end members 30 connecting said extensions to the opposite side frame, said sectional end pieces being capable of being folded inwardly to draw the side frames together, bearings secured in said extensions, a double crank provided 35 with trunnions mounted in said bearings, a bottom frame provided with eyes to receive said crank, said bottom frame being capable of being swung into vertical position within the extensions, and means for supporting 90 said bottom frame horizontally in different horizontal planes.

4. A folding crib and coop comprising wheeled side frames, one of said side frames being provided with lateral extensions, sectional end members connecting said extensions to the opposite side frame, a double crank pivotally mounted within said extensions, a fabric covered frame pivotally mounted upon said double crank, a strip secured to one of the side frames for supporting said bottom in lowered horizontal position, buttons carried by one of the side frames, and tapes carried by the bottom frame adapted to engage said buttons for 105 holding the opposite side of said bottom frame in raised horizontal position.

In testimony whereof I hereunto affix my signature.

PETER H. COLT.
